UNITED STATES PATENT OFFICE.

ADOLPH PELZER, OF TACOMA, WASHINGTON.

DESIGN FOR A COAT RACK.

Application filed January 16, 1924. Serial No. 8,326. Term of patent 14 years.

To all whom it may concern:

Be it known that I, ADOLPH PELZER, a citizen of Poland, formerly a part of Russia, having declared my intention to become a citizen of the United States of America, residing at Tacoma, in the county of Pierce and State of Washington, have invented a new, original, and ornamental Design for Coat Rack, of which the following is a specification, reference being had to the accompanying drawings, forming a part hereof.

I claim:

The ornamental design for a coat rack as shown.

ADOLPH PELZER.

In the presence of—

ARTHUR F. HOPPE.
